US00D582402S

(12) **United States Design Patent**
L'Henaff et al.

(10) **Patent No.:** **US D582,402 S**
(45) **Date of Patent:** **** Dec. 9, 2008**

(54) **HOUSING FOR AN ELECTRONIC DEVICE**

(75) Inventors: **Jean-Jacques L'Henaff**, Pelham, NY (US); **William Cowles**, Brooklyn, NY (US)

(73) Assignee: **Audiovox Electronics Corporation**, Hauppauge, NY (US)

(**) Term: **14 Years**

(21) Appl. No.: **29/266,014**

(22) Filed: **Sep. 13, 2006**

(51) **LOC (8) Cl.** **14-03**

(52) **U.S. Cl.** **D14/240**; D14/236

(58) **Field of Classification Search** **D14/242, D14/496, 240, 167, 302, 314, 348-358, 363, D14/383, 433, 140-140.9, 230-235; D13/149, D13/184; D3/201, 273; 379/220.01, 221.09, 379/220.14, 25, 93.09, 93.19, 156, 900, 338-339, 379/441; 711/100, 115; 361/658, 725, 752; 369/272.1, 273, 75.11; 360/133, 79.01, 97.03**

(57) **CLAIM**

The ornamental design of a housing for an electronic device, as shown and described.

DESCRIPTION

FIG. 1 is a front isometric view of a housing for an electronic device showing our new design;

FIG. 2 is a rear isometric view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof; and,

FIG. 8 is a left elevational view thereof.

The phantom lines are for illustrative purposes only and form no part of the claimed design.
